UNITED STATES PATENT OFFICE.

FRANK E. HILL, OF MORGANTOWN, WEST VIRGINIA.

CHUCK FOR HOLDING GLASS ARTICLES.

1,122,114.

Specification of Letters Patent. Patented Dec. 22, 1914.

Application filed April 9, 1914. Serial No. 830,724.

To all whom it may concern:

Be it known that I, FRANK E. HILL, a citizen of the United States, residing at Morgantown, in the county of Monongalia and State of West Virginia, have invented new and useful Improvements in Chucks for Holding Glass Articles, of which the following is a specification.

The present invention is directed to improvements in chucks for holding tumblers and similar articles of glassware during grinding and polishing.

Heretofore, it has been customary to equip glass-polishing, grinding, and like machines with a series of chucks of different sizes. These machines, as will be understood, are somewhat expensive to construct, and since each chuck can be used only with one particular size of tumbler or other article, the cost of installation and maintenance of a complete machine is very considerable. Moreover, the necessity for removing a chuck bodily from a machine, and the substitution therefor of another of different size, in order to permit the machine to operate upon a different size of article, is itself objectionable, owing to the loss of time occasioned thereby.

It is the purpose of this invention to remedy the aforementioned and other defects, by providing a chuck which can be used equally well with all of the different sizes of a given article and in which the change may be made without requiring that the chuck itself be detached. On the contrary, the only step necessary is the mere substitution of one element of the chuck for another, an operation which consumes but very little time and which may be carried out with perfect safety to the operative while the machine is running.

An embodiment of the invention is illustrated in the accompanying drawing, whereof:

Figure 1 is a fragmental side elevation of a glass-grinding machine equipped with the improved chuck; Figs. 2 and 3 are enlarged vertical sections taken axially through the chuck at right-angles to each other; Fig. 4 is a transverse section on line 4-4, Fig. 2; and Fig. 5 is a perspective view of the removable element of the chuck.

Referring more particularly to said drawing, 7 indicates the head-block of the machine wherein the horizontal shaft 8 that carries the grinding-wheel 9 is mounted, 10

the sliding tail-block, and 11 the track along which the latter travels. These parts are supported upon a frame 12, and they are, in the main, of conventional type, for which reason an extended description thereof is omitted, it being considered sufficient for present purposes to state that the tail-block is moved, through the agency of suitable devices, (not shown), toward and from the 60 grinding-wheel 9, which latter is rotated from a pulley 13 on shaft 8 connected by a belt 14, or in any other desired manner, with a source of power.

The improved chuck, which embodies the 70 most important features of this invention, as previously stated, is shown as carried by the tail-block, so as to move therewith into and out of operative position with relation to the grinding-wheel. As it is designed, in 75 the construction illustrated, to hold a tumbler, or similar cylindrical, or approximately cylindrical, article 16, its body 15 has, likewise, the form of a hollow cylinder or sleeve which is open at its front and closed at its rear end, the latter end being provided with a threaded, axial bore 17 for the reception of a threaded bolt 18 secured to the tail-block, as depicted in Figs. 2 and 3.

The interior of the chuck body receives the 85 tumbler, as will be understood, and, for this reason, is made sufficiently large to admit tumblers of widely varying diameters. In consequence, it becomes necessary to utilize with the chuck body some means whereby 90 all of the different sizes of tumblers may be held in place therein with equal facility, such means being readily insertible in and removable from the chuck body and capable of manufacture at a low cost in the several 95 stock sizes. The means in question preferably consists of a sleeve or ring-like member 19, best shown in Fig. 5, which is designed for insertion in the front or outer end of the chuck body, and is centered 100 by engaging a circumferential shoulder 20 formed in the inner wall thereof. This ring or sleeve is provided upon its inner wall, in turn, with a lining or pad 21 of rubber or other suitable material capable of 105 exerting a friction grip upon the surface of the inserted tumbler, as depicted in Figs. 2, 3 and 4, and in the present instance such lining consists of an annular band or strip that is fitted in a circumferential groove 110 22. The ring or sleeve, which thus acts as the holder proper, is so mounted within the

chuck body 15 that, while capable of removal therefrom, it must yet be normally locked in place therein. To this end, one of these two companion parts, in the present 5 instance the ring or sleeve itself, has formed in its outer surface a bayonet slot 23, while the other part, *i. e.*, the chuck body, has a lateral pin 24 secured to its inner wall for engagement therein. One branch of slot 23 10 opens through the rear edge of the ring or sleeve, while the other branch, (which is, of course disposed at an angle to the first-named or inlet branch), is of gradually-decreasing depth from its inner to its outer 15 end, so that when the pin has entered the aforesaid inlet branch and has reached the junction of that branch with the offset branch, rotation of the ring or sleeve in a clockwise direction, (Fig. 4), will cause the 20 inner end of the pin to exert a binding pressure against the bottom wall of the offset branch which gradually increases as the turning movement of the ring or sleeve continues. In practice, however, a very slight 25 turning movement only is necessary for the purpose stated, thus permitting rapid locking and unlocking of the ring or sleeve and, consequently, the substitution of one sleeve or ring for another.

30 While illustration of the invention has been confined to its application to a tumbler-holding chuck, it is to be understood that in its actual working, no such restriction is contemplated. On the contrary, it may be 35 here stated that the chucks may be so constructed as to accommodate other types or styles of glass articles, as will, in fact, be apparent, and in each instance a plurality of rings or sleeves 19 of different thicknesses 40 will be provided, in practice, for each chuck, to permit its use with different sizes of the particular article for which that chuck is designed.

In changing a chuck, all that is necessary 45 is to unscrew it from the threaded bolt, and then to screw the new chuck thereon, a proceeding which may obviously be carried out very rapidly; but it is to be understood that this change is only made when an article 50 of glassware of different type from that preceding it, is to be ground, polished or otherwise treated, and that a chuck is to all intents affixed to the tail-block during the time that any given style or type of article 55 is undergoing treatment.

I claim:—

1. A chuck for holding glass articles comprising a hollow body portion; and an annular member adapted to encircle the article 60 and to frictionally engage the same, remov-

ably fitted in the outer end of said body, said body and member constituting companion parts, one of which is provided with a bayonet slot and the other with a lateral pin removably engaged therein.

65

2. A chuck for holding glass articles comprising a hollow, cylindrical body portion; a ring removably fitted in the outer end thereof and adapted to frictionally engage the article, said ring being formed upon its outer surface with a bayonet slot, one branch of which opens through the rear edge of the said surface; and a lateral pin secured to the inner wall of said body for removable engagement in said slot.

75

3. A chuck for holding glass articles comprising a hollow body portion; an annular member removably fitted in the outer end of said body and adapted to encircle the article, said member being provided upon its inner surface with a circumferential groove; and a pad fitted in said groove and adapted to frictionally engage said article.

80

4. A chuck for holding glass articles comprising a hollow body portion which is open 85 at its front end and closed at its rear end, the latter end being provided with a threaded, axial bore, and an annular member removably fitted in the first-named end of said body and adapted to frictionally engage the 90 article; in combination with a threaded bolt having one end fitted in said bore, and a tail-block to which said bolt is secured.

95

5. A chuck for holding glass articles comprising a hollow body portion which is open 95 at its front end and closed at its rear end, the latter end being provided with a threaded, axial bore, and an annular member removably fitted in the first-named end of said body and adapted to frictionally engage the 100 article.

100

6. A chuck for holding glass articles comprising a hollow body portion which is open 105 at its front end and closed at its rear end and is formed upon its interior with a circumferential shoulder, the second-named end of said body being provided with a threaded, axial bore, and an annular member removably fitted in the first-named end of said body with its inner edge in contact 110 with said shoulder, said member being adapted to frictionally engage the article.

110

In testimony whereof I have hereunto set my hand in presence of two subscribing witnesses.
